(57) **CLAIM**

The ornamental design for a lavatory, as shown and described.

DESCRIPTION

In a preferred embodiment, the nature of this product is a lavatory for washing human body parts.

FIG. 1 is a top, left, front perspective view of a lavatory embodying my new design;

FIG. 2 is a top plan view thereof;

FIG. 3 is a left side elevational view thereof, the right side elevational view thereof being a mirror image of the left side shown;

FIG. 4 is a front elevational view thereof;

FIG. 5 is one possible rear elevational view thereof;

FIG. 6 is a top, left, front perspective view of a lavatory according to another embodiment my new design;

FIG. 7 is a top plan view thereof;

FIG. 8 is a left side elevational view thereof, the right side elevational view thereof being a mirror image of the left side shown;

FIG. 9 is a front elevational view thereof; and,

FIG. 10 is one possible rear elevational view thereof.

The broken line representations of holes and a drain in FIGS. 1-2 and 6-7 are for the purpose of illustration only, and form no part of the claimed design. Further, the rear views of FIGS. 5 and 10 are not seen in normal use. Thus, they also form no part of the claimed design.
